UNITED STATES PATENT OFFICE.

WILLIAM H. HILL, OF MANATI, PORTO RICO.

LIQUID-FUEL-VAPORIZING DEVICE.

Application filed May 8, 1918. Serial No. 233,233.

To all whom it may concern:

Be it known that I, WILLIAM H. HILL, a citizen of the United States, residing at Manati, Porto Rico, have invented certain new and useful Improvements in Liquid-Fuel-Vaporizing Devices, of which the following is a clear, full, and exact description.

This invention relates to apparatus for the treatment of liquid fuels to prepare them for use in combustion devices and particularly to apparatus for effecting the rapid, progressive and complete volatilization or vaporization of the more heavy or less volatile liquid fuel, such as kerosene, so as to render them available for convenient, efficient and economical use in combustion devices and especially in internal combustion motors. The invention is herein shown as embodied in an auxiliary device adapted to be used in connection with the usual carburetor of an internal combustion motor, but it will be understood that the invention is not restricted to the illustrated embodiment and uses, and that many features of the invention are of general utility in the art to which the invention relates.

A general object of the invention is to provide improved means for insuring or for effecting the rapid and complete volatilization or vaporization of a liquid fuel and particularly of the less volatile liquid fuels such as kerosene. The invention aims particularly to provide means for effecting such rapid and complete vaporization without cracking or other modification of the combustible character of any of the constituents of the fuel, and without at any time subjecting the fuel, while in its liquid state, to a temperature higher than that required to evaporate it, the invention aiming to separate a complex fuel into its component parts by fractional distillation and by evaporating each part substantially at its boiling point.

Devices for vaporizing the heavier liquid fuels as heretofore designed have usually been defective in that the operation of such devices would vary with variations in the atmospheric temperature. Moreover, the uniformity of operation of such devices has been seriously affected by the conduction of heat from one part of the device to another. This has been particularly true of vaporizing devices in which the vaporizing has been effected by the application of heat directly to the fuel to be vaporized. In such devices, when operated for any length of time, unless

manually adjusted or controlled, there has been a tendency to crack the more volatile constituents of the fuel, thus affecting to a very marked extent the combustibility of such constituents.

An important object of the present invention, therefore, is to provide means for utilizing heat in the vaporization of a liquid fuel which will so graduate the amount and intensity of the heat applied to the fuel in the different stages of its vaporization or volatilization that the intensity of the heat will not be sufficient, while the fuel still contains its more volatile constituents in liquid form, to affect injuriously the more volatile constituents, while preferably being sufficient, both in intensity and quantity, to effect the rapid vaporization or volatilization of such constituents. In a preferred embodiment of the invention the tendency of the heat to travel by conduction from one part of the apparatus to another has been utilized to effect the graduated or differential heating of the surface or surfaces through which the vaporizing heat is to be imparted to the fuel, thereby utilizing, to obtain the proper heating effect, that tendency in prior devices which has interfered with their proper operation.

An important feature of the present invention is the novel means for securing a differential heating of a vaporizing chamber in which the fuel to be vaporized is brought into contact with heated surfaces. Another important feature of the invention is the novel means for bringing each of the different constituents of the fuel into contact with a part of the heated surface which will impart thereto its appropriate heat of volatilization.

Other objects and important features of the invention will appear from the following description and claims when considered in connection with the accompanying drawings, in which—

Fig. 1 is a vertical section through liquid fuel vaporizing means embodying the present invention and intended to be used as an auxiliary device in connection with an ordinary carburettor;

Fig. 2 is a section on the line 2—2 of Fig. 1;

Fig. 3 is a section on the line 3—3 of Fig. 1; and

Fig. 4 is a perspective detail showing the construction of the part of the device which

directs the incoming gases to the outer wall of the device.

- The illustrated device comprises a cylindrical casing 2 having therein a volatilizing or vaporizing chamber into which the atomized and partly vaporized fuel from the carburetter is directed by a pipe or conduit 4, the pipe or conduit 4 being arranged at a tangent to the cylindrical wall of the casing
- 10 2. Said pipe or conduit 4 constitutes directing means whereby the incoming fuel is caused to travel along the inner surface of the wall of the cylinder, thus producing a centrifugal action in a horizontal plane upon
- 15 the constituents of the fuel, whereby the heavier constituents tend to displace the lighter ones toward the center of the vaporizing chamber. Those constituents which are already vaporized or volatilized are permitted to pass at once out of the vaporizing chamber through an outlet conduit 6 which may be connected to the manifold of an internal combustion motor, this conduit 6 being shown as formed integral with a cover
- 25 8 fitted to the upper end of the cylindrical casing 2, said casing 2 having at its lower end an integral bottom 10 provided with a hollow threaded boss 12 for a purpose hereinafter to be set forth.
- 30 When the device herein shown is connected to an internal combustion motor, the flow of atomized fuel into the vaporizing chamber through the intake conduit 4 will naturally be proportional to the demand made
- 35 upon the device by the motor, this demand being indicated by the suction produced by the intake strokes of the motor pistons, and therefore the degree of centrifugal action will be to some extent proportional to the
- 40 speed at which the atomized fuel is drawn into the vaporizing chamber through the intake 4. In order to make this centrifugal action as nearly uniform as possible for all demands made upon the device and at the
- 45 same time to further insure the direction of the fuel against the walls of the vaporizing chamber, a directing door or valve 14 is provided between the intake 4 and the vaporizing chamber, this door or valve being carried upon a vertical pivot 16 having its bearings in a casting 18 supported in the upper end of the chamber of the cylinder 2, the door or valve 14 being curved substantially to the curve of the inner wall of the cylindrical casing 2, and being normally held in position to close the intake 4 by means of a spring 20 connected at one end to an arm 22 upon the depending lower end of the pivot 16 and at its other end to a stud 24 upon the
- 50 underside of the casting 18.

The casting 18 comprises upper and lower plates 26 and 28 connected by an integral segment-shaped side plate 30, the plate 26 being shaped to fit the shouldered inner wall

55 of the cylinder 2, and the plate 28 extending

only part way across the cylinder and thereby providing an open space between the edge of said plate and the inner wall of the casing 2, through which the fuel may pass into the main vaporizing chamber. The 70 plate 26 is also provided with a central opening 32 fitting about the outlet pipe 6, and the plate 28 has a curved face 34 also bearing against said outlet pipe.

As hereinabove suggested, an important 75 feature of the invention is the means for producing a differential heating of the surfaces of the vaporizing chamber, into contact with which the fuel to be vaporized is brought. In liquid fuel vaporizing means 80 heretofore devised, difficulty has been experienced because of the substantially uniform heating of the contact surfaces. In such devices the unvolatilized portions of the fuel are all brought into contact with 85 surfaces heated to substantially the same degree of temperature, with the result that the more easily volatilized portions of the fuel are overheated and frequently cracked, resulting in the formation of compounds not 90 so readily combustible, with the resultant accumulation of carbon in the motor and the tell-tale black smoke from the exhaust, indicating imperfect combustion. This cracking of the fuel also causes the formation of 95 more readily combustible compounds, that is, unsaturated hydrocarbons, which produce the characteristic "knock" or "knocking" of internal combustion motors indicating pre-ignition, this "knocking" being analogous to 100 that produced by advancing the spark.

In the device herein shown, means is provided for heating the vaporizing chamber from the engine exhaust, the illustrated means comprising a jacket 36 about the 105 lower end of the cylindrical casing 2, this jacket being open at its upper end and fitting against a flange 38 upon the casing 2 and being provided in its bottom with an opening through which the hollow boss 12 110 upon the lower end of the casing 2 extends, this boss being threaded upon its outside to receive a nut 40 by which the jacket 36 may be clamped upon the casing 2. The jacket 36 has intake and outlet connections 42 and 44, 115 through which the exhaust from the engine may pass into and out of the chamber in the jacket 36 surrounding the casing 2.

In order to secure a differential heating of the chamber in the casing 2, means is 120 provided for intensifying the heating of the lower part of the chamber and for radiating away some of the heat which would normally be conducted to the upper part of the chamber. The illustrated means comprises radiating flanges 46 about the lower end of the casing 2 and within the jacket 36, these flanges serving to collect more of the heat of the exhaust and to conduct it through the wall of the casing 2 into the 130

lower end of the chamber within said casing, and other flanges 48 on said casing about the upper part of said chamber, the flanges 48 being exposed to the air and thus serving to radiate away some of the heat which would normally be conducted up through the wall of the casing 2. By this arrangement of flanges, a decided differential is produced between the temperature 5 of the wall surrounding the lower part of 10 the vaporizing chamber and that of the wall surrounding the upper part of said chamber.

From the foregoing description, the operation 15 of the device will be apparent. The atomized and usually partly vaporized fuel drawn into the device through the intake 4, as a result of the partial vacuum produced by the action of the motor pistons, 20 will pass through the passage between the partly opened valve or door 14 and the inner wall of the casing 2, the amount of opening of this valve or door 14 being proportioned to the amount of vacuum produced and the speed of travel of the fuel. 25 As it travels along the curved inner wall of the casing 2, the volatilized portions of the fuel will be displaced toward the center of the chamber and may pass out through 30 the outlet 6 as soon as they come below the lower end of this outlet. The unvolatilized portions of the fuel will continue to travel along the inner surface of the wall of the casing 2 and will gravitate 35 down this wall, thus moving gradually into zones of increasing temperature. As the more easily volatilized portions of the fuel reach portions of the surface which will impart to them their appropriate heats of 40 volatilization, they will be volatilized or vaporized and may at once pass out through the outlet 6. The heavier portions will then continue to move down the inner wall of the casing 2 until they also reach parts of 45 said wall which will impart to them their appropriate temperatures of volatilization, when they also will be vaporized and separated from the still less volatile parts. This fractional and progressive distillation or 50 volatilization of the constituents of the fuel will continue until the least volatile portions having reached the hotter parts of the wall are finally vaporized.

In order further to insure the travel of 55 the less volatile portion of the gases down the inner wall of the casing 2, a ledge 50 may be provided about the lower part of the outlet pipe 6, this ledge having a flange 52 forming a trough or spill pan about the 60 pipe 6, and the flange 52 being so spaced from the inner wall of the casing 2, as shown at 54, as to provide a narrow passage through which the fuel must pass down into the main part of the gasifying chamber. Any fuel brought in in a purely liquid 65

condition, which does not pass down through the space 54 but which accumulates in the trough or spillway provided by the ledge 50 and flange 52, will be gradually fed into the space 54, running through the openings 70 57 of the flange 52 and then along the legs 55 to the inner wall of the chamber and then down said wall, and thus subjected to the volatilizing action of the heated walls of the chamber in the casing 2. 75

In order to insure bringing the unvolatilized portions of the fuel, which travel to the lower part of the chamber in the casing 2, into close proximity to the inner wall of said casing, a closed cylinder 56 may be 80 located in this part of the chamber and spaced from the walls thereof by any suitable means, such, for example, as the studs 58. This usually only happens when the engine is idling or under low speed conditions. 85

The hollow boss 12 is threaded on the inside at 41 to receive a plug (not shown) by which it is normally closed, the plug being removable to drain any sediment 90 which may accumulate in the vaporizing chamber.

This application, as to common subject-matter, is a continuation of my co-pending application, Serial No. 211,333, filed January 11, 1918. 95

What I claim as new is:—

1. A liquid fuel vaporizing device comprising, in combination, a vaporizing chamber having a differentially heated wall surface onto which the liquid fuel is directed and over which it passes in the direction of increasing heat, and means for heating said surface arranged to cause the hotter part of said surface to be heated by conduction 100 through the wall and for causing the less heated parts of said surface to be heated only by conduction along the wall. 105

2. A liquid fuel vaporizing device comprising, in combination, a vaporizing chamber having a differentially heated wall surface onto which the liquid fuel is directed and over which it passes in the direction of increasing heat, and means for heating said surface arranged to cause a part of said surface to be heated by conduction through the wall and for causing another part of said surface to be heated only by conduction along the wall, and heat collecting means carried by the first mentioned part of said wall for emphasizing the differential heating. 110 115

3. A liquid fuel vaporizing device comprising, in combination, a vaporizing chamber having a differentially heated wall surface onto which the liquid fuel is directed and over which it passes in the direction of increasing heat, and means for heating said surface arranged to cause a part of said surface to be heated by conduction through 120 125 130

the wall and for causing another part of said surface to be heated only by conduction along the wall, and heat radiating means carried by the last mentioned part of said wall for emphasizing the differential heating.

4. A liquid fuel vaporizing device comprising, in combination, a vaporizing chamber having a differentially heated wall surface onto which the liquid fuel is directed and over which it passes in the direction of increasing heat, and means for heating said surface arranged to cause a part of said surface to be heated by conduction through the wall and for causing another part of said surface to be heated only by conduction along the wall, and heat collecting means carried by the first-mentioned part of said wall and heat radiating means carried by the last-mentioned part of said wall for emphasizing the differential heating.

5. A liquid fuel vaporizing means comprising a vaporizing chamber having there-in a surface heated by means external to said chamber, part of said surface being heated by conduction through the wall upon which said surface is formed and a part being heated only by conduction along the wall and in such manner that the heat of said surface gradually increases through the range of heats of volatilization of the constituents of the fuel to be vaporized, and means for directing the fuel to be vaporized into said chamber and upon and over said surface in such manner that it travels in the direction of increasing heat.

6. A liquid fuel vaporizing means comprising a chamber having a vertical wall, means external to said chamber for heating said wall, means for facilitating collection of heat by said wall along one part of said wall, and means for facilitating radiation of heat away from said wall along an adjacent part of said wall, whereby a differentially heated inner surface is presented in said chamber, and means directing the fuel to be vaporized upon and over said heating surface from the region of least heat to the region of greatest heat.

50 7. Liquid fuel vaporizing means comprising a chamber having the inner surface of its outer wall arranged to constitute volatilizing means over which the liquid fuel gravitates, and means external to said chamber and opposed to the lower part of said surface for imparting heat to said surface by conduction through the wall, the part of said wall above said means being unexposed to said means and arranged to be heated only by conduction along said wall.

8. Liquid fuel vaporizing means comprising a chamber having the inner surface of its outer wall arranged to constitute volatilizing means over which the liquid fuel gravitates, means external to said chamber

and opposed to the lower part of said surface for imparting heat to said surface by conduction through the wall, the part of said wall above said means being unexposed to said means and arranged to be heated only by conduction along said wall, and centrally arranged means for conducting away from said chamber the vaporized fuel.

9. Liquid fuel vaporizing means comprising, in combination, a chamber presenting a fuel heating surface over which the liquid fuel to be vaporized is caused to travel in a film, means for heating said surface, and means adjacent to that part of said surface over which the fuel first travels for radiating away a portion of the heat, whereby said fuel travels over a differentially heated surface in the direction of increasing heat.

10. Liquid fuel vaporizing means comprising, in combination, a chamber presenting a fuel heating surface over which the fuel to be vaporized is caused to travel in a film, means for so heating said surface that it will raise the various constituents of the fuel to their volatilizing temperatures, and means adjacent to that part of the surface over which the fuel first travels for so radiating away a portion of the heat that the temperature of this part of said heating surface, while sufficient to volatilize the more volatile constituents of the fuel, is not sufficient to crack said constituents before volatilization.

11. In a device of the class described, the combination with means for separating the unvolatilized from the volatilized parts of a fuel mixture, of volatilizing means arranged to exert a volatilizing action on the separated unvolatilized parts of the fuel to an extent and in a succession determined by the volatility of said parts.

12. In a device of the class described, the combination with means for effecting a centrifugal movement about a vertical axis of a fuel mixture, whereby the unvolatilized parts of said fuel are separated from the volatilized parts, of heating means in which the separated unvolatilized parts of the fuel gravitate through zones of gradually increasing heat.

13. In apparatus of the class described, adapted to be placed between the carburetter and the intake of an internal combustion motor, the combination with centrifugal means for separating the unvolatilized from the volatilized parts of the fuel mixture, of means for progressively volatilizing the separated unvolatilized parts of the fuel mixture constructed to permit the immediate discharge of each part as it is volatilized.

14. In apparatus of the class described, adapted to be placed between the carburetter and the intake of an internal combustion motor, the combination with a cylindrical chamber and a tangentially arranged inlet

- 5 pipe, of means supplementing the action of said tangential inlet pipe and controlled by the rate of flow of the atomized fuel through said apparatus, for directing the incoming fuel against the wall of said chamber.
15. In a device of the class described, adapted to operate upon the fuel between the carburetter and the intake of an internal combustion engine, the combination with a centrifugal chamber having a central outlet, of a yielding baffle in the path of the incoming fuel arranged to direct said fuel toward the outer wall of said chamber.
16. In a device of the class described, 15 adapted to be located between the carburetter and the intake of an internal combustion motor, a cylindrical chamber having a vertical axis and having a central outlet, means for directing the incoming atomized fuel 20 against the wall of said chamber, and means for so differentially heating the wall of said chamber below said inlet as to effect the progressive vaporization of the unvaporized portions of said fuel as they travel down 25 said wall.
17. In apparatus of the class described, the combination with a vertically arranged cylindrical chamber having an inlet near its upper end and an axially arranged outlet, of means for directing the unvolatilized portions of the fuel entering said chamber onto the cylindrical wall of said chamber, means for heating the lower end of said wall and radiating means for radiating away a part 35 of the heat conducted to the upper part of said wall.
18. In a liquid fuel vaporizing apparatus, the combination with a vertically elongated chamber having a centrally arranged outlet at its upper end, of means for so differentially heating the wall of said chamber 40 as to cause the zone of most intense heat to be at the lower end of said chamber, and means for introducing liquid fuel to be vaporized into said chamber, comprising 45 means for directing said fuel first against the upper less heated part of the wall of said chamber.
19. In a device of the class described, 50 adapted to be located between the carburetter and the intake of an internal combustion motor, the combination with a cylindrical chamber having a vertical axis and having a central outlet and a tangentially arranged inlet pipe, whereby centrifugal separation of the volatilized from the unvolatilized parts of the atomized fuel is effected, of means for so differentially heating the wall of said chamber below said inlet 55 as to effect the progressive volatilization of the unvolatilized portions of said fuel as they travel down said wall.
20. In an apparatus of the class described,
- the combination with a cylindrical chamber having a vertical axis and having a tangentially arranged inlet near its upper end and an axially arranged outlet, of means external to said chamber for heating the lower end of said chamber, a part of the wall of said chamber above said heated lower end 65 being unexposed to said means, exposed to the surrounding air and heated only by conduction along said wall.
21. In an apparatus of the class described, the combination with a vertically arranged cylindrical chamber having a tangential inlet near its upper end and an axially arranged outlet opening into said chamber below said inlet, of means for differentially heating the wall of said chamber comprising 70 means for directly imparting heat to the lower part of the wall of said chamber, the part of the wall of said chamber above said means being unexposed to said means, exposed to the surrounding air and arranged 75 to be heated only by conduction along said wall.
22. In apparatus of the class described, adapted to be located between the carburetter and the intake of an internal combustion engine, the combination with a vertically arranged cylindrical chamber having a tangential inlet and an axially arranged outlet, of a spring-controlled valve in said inlet arranged to direct incoming fuel 80 against the wall of said chamber to effect a centrifugal action upon the constituents of said fuel, means for directing the motor exhaust over the lower part of said chamber, and heat collecting means upon the 85 outer wall of said chamber within said exhaust for intensifying the heat in the lower part of said chamber.
23. In apparatus of the class described, 90 adapted to be located between the carburetter and the intake of an internal combustion engine, the combination with a vertically arranged cylindrical chamber having a tangential inlet and an axially arranged outlet, of a spring-controlled valve in said 95 inlet arranged to direct incoming fuel against the wall of said chamber to effect a centrifugal action upon the constituents of said fuel, means for directing the motor exhaust over the lower part of said chamber, heat collecting means upon the outer 100 wall of said chamber within said exhaust for intensifying the heat in the lower part of said chamber, and heat radiating means above the exhaust heated portion of said 105 chamber for radiating away a part of the conducted heat.

Signed at New York city, this 30th day of April, 1918.

WILLIAM H. HILL.
